UNITED STATES PATENT OFFICE.

EDWARD MULLER, OF NORTH BERGEN, NEW JERSEY.

BY-PASS VALVE.

Application filed October 21, 1927. Serial No. 227,711.

The objects of this invention are to provide a by-pass valve, such as for pumps and the like, which will operate quietly and without hammering or pounding; to secure such a valve, having interior springs, in which the tension of said springs can be adjusted from the outside of the valve; to enable ready access to the valve stem packing, at the same time, and to obtain other advantages and results as may be brought out by the following description.

Referring to the accompanying drawings, in which like characters of reference indicate the same parts throughout the several views,

Figure 1 is a central longitudinal section of a by-pass valve of my improved construction, showing it closed;

Figure 2 is a similar view showing the position of certain parts when the valve is partially closed;

Figure 3 is a plan of the valve, and

Figure 4 is a cross-section on line 4—4 of Fig. 1.

In the specific embodiment of the invention shown in said drawings, the valve body 1 has inlet and outlet passages, 2 and 3 respectively, separated by a diaphragm or partition 4 through which is a valve opening 5 disposed in a plane at substantially right angles to the planes of the inlet and outlet passages 2 and 3 and having at the inlet side thereof a valve seat 6 with which cooperates a valve head 7 carried by a stem 8, which at the inlet side of the seat 6 projects from the valve body 1 and is slidably mounted in the wall thereof and at the outlet side of the seat 6 has its end slidably mounted in a cap 9 which closes the valve chamber. The stem 8 is normally influenced by a compression spring 10 to move the valve head 7 against its seat 6 to close the valve opening 5, said spring being interposed between the cap 9 and a piston disk 11 fast on the valve stem 8 and being loosely slidably in a cylinder which is here shown as the outer chamber 12 of a double-ended cup 13 whose inner chamber 14 slidably receives the valve head 7 to retard its closing movement onto its seat 6 and thereby prevent hammer action of the valve head upon the seat. This double-ended cup 13 is slidably loose upon the valve stem 8, and the open end of its inner chamber 14 is arranged to abut against the partition 4 of the valve body around the valve seat 6, being normally influenced to-

ward said partition by a light compression spring 15 interposed between the transverse wall 16 of the double cup and the piston disk 11. The inner chamber 14 of the cup 60 is longer than the thickness of the valve head 7, and its side wall is formed adjacent the end edge thereof with a plurality of small transverse openings 17 which permit water to flow into the chamber 14 when the 65 cup is seated upon the partition 4.

When the valve is in normal closed position, the parts are located as shown in Figure 1, the valve head 7 being seated upon the seat 6 and the inner end edge of the cup 13 70 abutting against the partition 4, the openings 17 in the side wall of the cup being covered by the valve head 7. Obviously, the space in the inner chamber 14 of the cup, behind the valve head 7 will be filled with water, and as 75 the valve stem 8 is moved by opening of the valve, the valve head 7 is moved from its seat 6 and carries the cup 13 with it away from the partition 4. Free flow of water is thus permitted from the inlet passage 2 80 through the valve opening 5 to the outlet passage 3. While the valve remains in open position, the spring 15 gradually forces the cup 13 toward the partition 4, so that the transverse wall 16 of the cup rests upon the 85 valve head 7. The proportion of the parts, however, is such that the valve head holds the cup away from the partition 4 to permit free flow of the water through the valve opening 5.

When the valve stem moves to close the valve, the edge of the cup 13 strikes the partition 4 before the valve head reaches the seat 6, as shown in Figure 2 of the drawings. The movement of the valve head toward the 90 seat is then retarded, due to the fact that it must move relatively to the cup 13, and such motion in the cup 13 creates a suction between the valve head and the transverse wall 16 of the cup, which causes some of the water 100 flowing through the side openings 17 of the cup to pass between the valve head and the walls of the cup into the space between the transverse wall of the cup and the valve head. The passages thus provided, however, 105 are so small that movement of the valve head is necessarily slow, and accordingly the valve head approaches its seat 6 slowly and easily and without any material impact or hammering action. Such retardation is further increased by the piston disk 11 having to slide in the outer chamber 12 of the cup and

force out, past itself, the water therein between the said piston disk and the transverse wall 16 of the cup. Obviously this additional retardation could be eliminated, if desired, by omitting the outer chamber 12 of the cup 13 and utilizing the piston disk 11 merely as a spring stop or rest.

The valve stem 8 projects from the valve body 1 through a boss 18 thereon, said boss receiving packing around the stem and having a gland or nut 19 to clamp said packing. The lower part of the boss 18 provides a seat for the circular apertured portion of a bracket 20 which has opposite upwardly and inwardly curving arms 21, 21 supporting at their upper ends a transverse bar 22 apertured at its middle to slidably receive the stem 8 and afford a seat for a spring 23 between said seat and an adjustable stop upon the end of the stem, which stop is shown comprising a washer 24 with a nut 25 and lock-nut 26 outside of said washer. This spring 23 acts in conjunction with the spring 10 within the cap 9 of the valve, to seat the valve head 7, and further enables the spring pressure for seating said valve head to be adjusted and regulated; for while the inside spring 10 cannot be changed or regulated, the outer spring 23, by means of its nuts 25, 26 can be tightened or loosened to alter the tension upon the valve head 7 to seat the same. Furthermore, the outwardly bowed arms 21, 21 of the bracket 20 provide free and ready access at all times to the packing nut or gland 19 to adjust the same.

It will be noted that regulation of the spring pressure to seat the valve head 7 affects the relative movement and action of said valve head and the cup 13 or its inner apertured chamber, and thus I provide a by-pass valve which can be readily regulated to suit different conditions, wholly from the outside of the valve and without taking the same apart.

Various detail modifications may be made in manufacturing my invention, by those skilled in the art, without departing from the spirit and scope of the invention, and therefore I do not wish to be understood as limiting myself except as required by the following claims when construed in the light of the prior art.

Having thus described the invention, what I claim is:

1. A by-pass valve, comprising a body having an inlet and an outlet separated by a partition with a valve opening surrounded by a valve seat at the outlet side, a slidable valve stem projecting from the valve body at the inlet side and having a valve head fixed on said stem to cooperate with said valve seat, a spring on said stem normally seating the valve head, a cup slidable upon said valve stem providing a cylinder for the valve head with its open end arranged

to abut said partition around said valve seat and having lateral openings near said open end, a spring normally influencing said cup toward said partition so that said cup after being moved away from said partition by the valve head in opening will engage said partition in advance of the valve head in closing, and an adjustable spring upon the valve stem outside the valve body for changing the action of the said spring for seating the valve head in relation to the cup spring.

2. A by-pass valve, comprising a body having an inlet and an outlet separated by a partition with a valve opening surrounded by a valve seat at the outlet side, a slidable valve stem projecting from the valve body at the inlet side and having a valve head fixed on said stem to cooperate with said valve seat, a spring on said stem normally seating the valve head, a cup slidable upon said valve stem providing a cylinder for the valve head with its open end arranged to abut said partition around said valve seat and having lateral openings near said open end, a spring between said cup and a stop on the stem normally influencing said cup toward said partition so that said cup after being moved away from said partition by the valve head in opening will engage said partition in advance of the valve head in closing, and an adjustable spring upon the valve stem outside the valve body for changing the action of the said spring for seating the valve head in relation to the cup spring.

3. A by-pass valve, comprising a body having an inlet and an outlet separated by a partition with a valve opening surrounded by a valve seat at the outlet side, a slidable valve stem projecting from the valve body at the inlet side and having a valve head fixed on said stem to cooperate with said valve seat, a spring on said stem normally seating the valve head, a cup slidable upon said valve stem providing a cylinder for the valve head with its open end arranged to abut said partition around said valve seat and having lateral openings near said open end, a spring normally influencing said cup toward said partition so that said cup after being moved away from said partition by the valve head in opening will engage said partition in advance of the valve head in closing, and an adjustable spring upon the valve stem outside the valve body which increases the closing action of said spring for seating the valve head and changes the closing action with respect to the cup spring.

4. A by-pass valve, comprising a body having an inlet and an outlet separated by a partition with a valve opening surrounded by a valve seat at the outlet side, a slidable valve stem projecting from the valve body at the inlet side and having a valve head fixed on said stem to cooperate with said valve seat, a spring on said stem normally

seating the valve head, a cup slidable upon said valve stem providing a cylinder for the valve head with its open end arranged to abut said partition around said valve seat 5 and having lateral openings near said open end, a spring normally influencing said cup toward said partition so that said cup after being moved away from said partition by the valve head in opening will engage said 10 partition in advance of the valve head in closing, a packing for the stem where it projects from the valve body, a bracket upon the valve body providing a support around the stem outwardly beyond said packing, and 15 a spring upon the stem between said support and an adjustable stop on the stem for changing the action of the valve-seating spring relative to the cup-seating spring.

5. A by-pass valve, comprising a body 20 having an inlet and an outlet separated by a partition with a valve opening surrounded by a valve seat at the outlet side, a slideable valve stem projecting from the valve body at the inlet side and having a valve head

fixed on said stem to cooperate with said valve seat, a spring on said stem normally seating the valve head, a cup slidable upon said valve stem providing a cylinder for the valve head with its open end arranged to abut said partition around said valve seat 25 and having lateral openings near said open end, a spring normally influencing said cup toward said partition so that said cup after being moved away from said partition by the valve head in opening will engage said partition in advance of the valve head in closing, a packing boss and gland upon the outside of the valve body around said stem, a bracket 30 mounted upon said boss next the valve body and having opposite outwardly bowed arms providing access to the packing gland, a cross-bar upon the ends of said arms apertured to receive the stem, an adjustable nut 35 upon the outer end of the stem, and a spring on said stem between said nut and bar for 40 changing the action of the valve-seating spring in relation to the cup-seating spring.

EDWARD MULLER.
